CLAIM

The ornamental design for a housing for portable telephone, as shown and described.

DESCRIPTION

FIG. 1 is a top, front and left side perspective view of a housing for portable telephone showing our new design; FIG. 2 is a bottom plan view thereof;

FIG. 3 is a rear elevation view thereof; and,

FIG. 4 is a right side elevational view thereof.

The broken line showings in FIGS. 1-4 are for illustrative purposes only and form no part of the claimed design.
